(57) **CLAIM**

The ornamental design for a compact wired transmitter with external configuration features for hazardous locations, as shown and described.

DESCRIPTION

FIG. 1 is a right side perspective view of a compact wired transmitter with external configuration features for hazardous locations;

FIG. 2 is a left side perspective view thereof;

FIG. 3 is a front elevation view thereof;

FIG. 4 is a back elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines shown in FIGS. 1-6 and 8 represent unclaimed subject matter and form no part of the claimed design.
